UNITED STATES PATENT OFFICE

1,928,427

CINEMATOGRAPHIC PROJECTOR

Charles Edward Hillery-Collings, London, England, assignor to Cam Syndicate Limited, London, England, a British company

Application February 25, 1932, Serial No. 595,102, and in Great Britain March 16, 1931

2 Claims. (Cl. 88—24)

This invention relates to cinematographic projectors, and especially to lighting means therefore of the kind in which a lamp and condenser in a tubular housing are arranged to be attached to the projector.

According to the invention the lamp housing is so fitted as to be capable of rocking about its longitudinal axis to open and close the electrical circuit through the lamp. A strip of spring metal 10 constituting a part of the electric circuit may be arranged to engage the central contact of the lamp in one position of the housing, the circuit being broken when the housing is rocked into the other position. The portion of the housing 15 wherein the lamp is inserted may be tapered, and is split to facilitate the insertion of the lamp, which is carried in a socket shaped to make a ball and socket joint with the housing, and tightened up by means of a clamping ring, which may be 20 screw threaded to engage the said split and tapered portion, or may be tightened by a suitable clamping screw, to hold the lamp in a set position. The socket can therefore be adjusted to compensate for any inaccuracy in the position of the 25 lamp filament, and the lamp housing may be perforated at both sides opposite the lamp filament, to facilitate checking the correctness of the filament's position relatively to the usual concave mirror, by sighting the filament through both 30 perforations. When once adjusted, the tubular housing can always be instantly inserted or withdrawn without affecting the adjustment of the lamp. In this way the maximum lighting effect relatively to the power of the lamp is obtained.

35 In order that the said invention may be clearly understood and readily carried into effect, the same will now be more fully described with reference to the accompanying drawing, wherein,

Figure 1 is a front elevation representing the 40 lighting device in its operative position.

Figure 2 is a similar view representing the device rocked into its inoperative position.

Figure 3 is a side elevation viewed from the interior of the projector.

45 Figure 4 is a side elevation of the housing detached, viewed from the side opposite to that seen in Figure 3, with the clamping ring detached.

Figure 5 is a perspective view of a clip suitable for securing the lamp housing within the projector casing.

50 Figure 6 is a representation of the lamp detached with the ball in section.

In the drawing, 91 indicates a portion of the projector casing, 92 a clip having a circular opening 93 and horizontal legs 94, 95 adapted to en-

gage a suitable guide projection formed on the casing. In this clip is lodged a tubular housing 97, at one end 98 of which is the concave mirror known as the radial mirror, and at the other end 99 of which are the condenser lenses arranged 60 in the usual manner, this housing 97 having an upward extension 100 split at 101 (Figures 1 and 2) to receive the ball 102 which is screwed on to the lamp 103 as seen in Figure 6. This extension 100 may be tapered and screw threaded with a 65 tapered screw thread and an internally screw threaded clamping ring 104 may be tightened thereon to secure the lamp socket in the said extension in a position in which the lamp filament is opposite the holes 105, 106 (Figures 3 70 and 4) in the housing. A pin 107 projects from the housing 97 through a slot 108 in the casing 91, and when this pin is depressed as seen in Figure 1, the lamp contact 109 engages a fixed contact 110 on the casing 91 to close the electrical 75 circuit and cause light to be emitted from the lamp, but when the pin 107 is pressed up into the position seen in Figure 2, the housing 97 is thereby rocked to break the circuit by taking the lamp contact 109 away from the fixed contact 110. 80

What I claim and desire to secure by Letters Patent of the United States is:—

1. In a cinematographic projector, a casing having a slot in its side, a strip of spring metal 85 on said casing forming a part of an electrical circuit, a tubular lamp housing, means on said casing to carry said housing, said means permitting angular movement of said housing about its axis, a lamp adjustably carried in said housing and having a terminal directed at right angles 90 to said axis, a projection on said housing extending through said slot and adapted to be actuated to rock said housing about its axis to bring said terminal into and out of contact with said strip, whereby the electrical circuit through said lamp 95 is closed and opened respectively.

2. A cinematographic projector including the combination, with a casing, of a projecting strip of spring metal on said casing forming part of an electrical circuit, a tubular lamp housing, means on said casing to carry said housing, which means provide for angular movement of said housing about its axis, a lamp in said housing having a terminal normally directed toward said strip of spring metal, and means adapted to shift said housing upon its axis so as to bring said lamp terminal into and out of contact with said strip in order to close and open the electrical circuit through said lamp respectively.

CHARLES EDWARD HILLERY-COLLINGS. 110
